LIFTING JACK

Joseph J. Mizer, Racine, Wis., assignor to Walker Manufacturing Company, Racine, Wis., a corporation of Wisconsin

Application October 12, 1934, Serial No. 748,101

20 Claims. (Cl. 254—6)

This invention relates to certain new and useful improvements in lifting jacks, and more particularly to an improved jack of the type which is mounted on a carriage and is provided with a relatively long, permanently attached operating handle by means of which the jack may be pushed into position beneath the load, elevated or lowered and moved while supporting the load. The present improvements are concerned especially with an auxiliary mechanism for quickly moving the load-lifting element into engagement with the load before the normal lifting operation is started.

The lifting jack to which these improvements are applied is substantially of the type disclosed and claimed in the patent to Warren H. Walker, 1,949,095, granted February 27, 1934. Briefly described this jack comprises a carriage in which is mounted a pivoted lifting arm in the form of a modified bell-crank lever adapted to support the load at the end of its longer arm and provided in its shorter arm with an internal arcuate rack which is in mesh with a rotatable driving pinion mounted on a shaft supported in the carriage and projecting through an opening in the lifting lever. The operating handle is pivoted at one end in the carriage and is adapted to be swung or oscillated through a small arc, suitable pawl and ratchet mechanism being interposed between the handle and pinion so that this driving pinion will be rotated, step by step, in one direction or the other as the operating handle is oscillated.

The improved quick-lift mechanism comprises a second pinion mounted to rotate with the first pinion, a rack suitably guided in the carriage and meshing with this second pinion, and a slide member mounted on the handle and connected with this rack. The jack is first pushed into position beneath the load by means of the handle and then by moving the slide member along the handle the load-lifting lever is quickly swung up into engagement with the load. The handle is then oscillated and the load lifted step by step by means of the pawl and ratchet mechanism.

The principal object of this invention is to provide an improved lifting jack of the type briefly described hereinabove and disclosed more in detail in the specifications which follow.

Another object is to provide an improved quick-lift mechanism for lifting jacks.

Other objects and advantages of this invention will be more apparent from the following detail description of one approved form of mechanism

constructed and operating according to the principles of this invention. In the accompanying drawings:

Fig. 1 is a side elevation of the complete jack, the elevated position of the lifting lever, and also alternative positions of the operating handle, being indicated in dotted lines.

Fig. 2 is a plan view of the jack, on a larger scale, a portion of the operating handle being broken away.

Fig. 2a is a plan view of the remainder of the operating handle, this view being substantially an extension of the right hand portion of Fig. 2.

Fig. 3 is a partial vertical section, this view being taken substantially on the line 3—3 of Fig. 2.

Fig. 4 is a partial vertical section on a larger scale, taken substantially on the same plane as Fig. 3.

Fig. 5 is a partial vertical section, taken substantially on the line 5—5 of Fig. 2.

Fig. 6 is a transverse vertical section, on a larger scale, taken substantially on the line 6—6 of Fig. 3.

Fig. 7 is a perspective view of the pinion and ratchet assembly, partially broken away.

Fig. 8 is a detail elevation of this pinion and ratchet assembly, the ratchet wheel being shown in vertical section.

The carriage comprises a pair of similar side frames 1 and 2 which are of greatest height adjacent their rear ends, and tapered toward the narrow front end portions which are connected and spaced apart by the front axle 3 which passes through hubs 4 on the side frames and is pinned thereto at 5. Wheels 6 are journaled on the outwardly extending ends of the axle 3 and are held in place by cotter pins 7 or other suitable fasteners. The ends of the side frames project forwardly to form feet 8 so that the jack may be stood up on end when not in use. Rollers 9 are journaled on the outwardly projecting end portions of a rear axle 10 mounted in the rear portion of the side frames. Intermediate portions of the side frames are connected and spaced apart by several pins and shafts hereinafter described.

The main lifting lever 11 has its forked rear end portion formed with a pair of hubs 12 and 13 journaled on the enlarged central portion of a fulcrum pin 14 which has reduced end portions 15 extending through bosses 16 formed on the respective side frames, the fulcrum pin being clamped in position between the side frames by 55

means of nuts 17 threaded on the opposite end portions of the pin. This lifting member also comprises a rack segment 18 having an upper central hub 19 positioned in the fork of the lever 5 and journaled on pin 14 between the hubs 12 and 13, and having its forwardly extending upper portion 20 secured by rivets 21 and 22 between downwardly extending flanges 23 of the main lever member 11. The downwardly extending 10 portion of segment 18 is formed beneath the hub 19 with an opening, and a concave internal rack or gear segment 24 is formed in the lower portion of this opening. This rack is arcuate and substantially centered in the axis of fulcrum pin 14, the several teeth 25 of the rack projecting inwardly and upwardly toward this fulcrum pin or axis. The lever 11 and segment 18 are rigidly connected, as already described, so as to form a single bell-crank lever mechanism which is adapted 15 to swing about the fulcrum pin 14. The long forwardly projecting arm of the bell-crank is pivoted at 26 to the lifting head or cap 27 which may be of any desired form and is preferably provided with the spaced apart upwardly extending 20 load-supporting fingers 28. A pair of similar side links 29 have their forward ends pivoted at 30 to the head 27 and their rear ends pivoted at 31 to the respective side frames 1 and 2. These links cooperate with the lever 11 to give a parallel 25 motion to the load-supporting head 27 so as to keep the head horizontal in all of its raised or lowered positions. The head is shown lowered in Figs. 1 and 3 and is shown in dotted lines in its elevated position in Fig. 1. It will be noted that 30 when this head is lowered to its extreme position it is substantially no higher than the tops of the wheels 6 at the front end of the carriage so that this load-supporting head may be pushed beneath very low hanging loads.

40 A fixed shaft 32 extends transversely through the opening in segment 18 and has its end portions mounted in bosses 33 formed in the respective side members 1 and 2, the reduced end portions 34 of the shaft extending outwardly through 45 the side members and the shaft being secured in place and to the side members by nuts 35. The operating assembly mounted rotatably on the central portion of shaft 32 (see Figs. 6, 7 and 8) comprises the main driving pinion 36 which 50 meshes with the teeth 25 of the internal rack 24 in the lifting lever. The ratchet wheel 37 is broached out to fit over one reduced end portion 38 of pinion 36, the teeth of the pinion forming keys for rigidly securing the ratchet wheel 37 to the pinion. The auxiliary pinion 39 (which forms a portion of the quick-lift mechanism hereinafter described) is also rotatably mounted on shaft 32 and is formed in one side with slots 55 to receive the lugs 39' extending from the end of driving pinion 36 opposite from the ratchet 37. This will cause the two pinions 36 and 39 to rotate as a unit. This rotating assembly is so positioned on the shaft 32 that the main driving pinion 36 will be within the opening in the segment 18 and mesh with the internal rack, whereas the ratchet wheel 37 will be positioned at one side of the bell-crank and the second pinion 39 at the opposite side.

70 The operating handle comprises a yoke casting 40 having forwardly extending side portions 41 and 42 which are journaled at their inner ends on the shaft 32 at the respective sides of the rotating assembly previously described, and just inside of the side frames 1 and 2 respectively.

75 The similar side bar members 43 and 44 of the

handle are secured at their forward ends in the recessed outer sides of the yoke casting 40 by means of bolts 45. The side bars 43 and 44 converge inwardly and rearwardly toward one another and are secured by bolts 46 to the opposite sides of the inner end of the handle extension bar 47. (See Fig. 2a). Suitable handle members 48 of wood or other suitable material are secured to the opposite sides of the extreme outer or rear end of the bar 47 thus completing the operating lever. In order to manipulate the raising and lowering mechanism, this operating handle is adapted to be reciprocated or oscillated vertically, different positions of the handle being indicated in dotted lines in Fig. 1. 15 The downward swinging movements of the handle are limited by the engagement of a stop or stops 49 formed on one or both of the side members 41 and 42 of yoke 40 with the rear shaft 10 of the carriage, and the upward movements of 20 the handle are limited by the engagement of one of the side arms (in the present example arm 42) with a stop screw 50 mounted in a lug 51 extending inwardly from side frame 2. A continued upward movement of the handle after it 25 has engaged with stop 50 will raise the rear end of the carriage so as to support same entirely by the front wheels 6 and thus facilitate moving the carriage in position.

An operating pawl or dog 52 is journaled on a 30 stud 53 mounted in the handle yoke arm 41 so that the pawl will be positioned substantially in the vertical plane of ratchet wheel 37. This pawl has a tooth 54 shaped to engage the teeth of ratchet 37 and is formed with a lug or projection 35 on one side thereof to cooperate with the rotary reversing member hereinafter described. A torsion spring 56 is anchored at one end and engages the pivoted pawl at the other to swing the pawl into engagement with ratchet 40 wheel 37 at all times. A holding pawl 57, which may be similar in all respects to the operating pawl 52, is mounted on a pin 58 which is mounted in the opposite side frames 1 and 2. Suitable spacers position the holding pawl 57 so that it 45 will also be in the vertical plane of ratchet wheel 37. The holding pawl is normally forced yielding into engagement with the ratchet wheel by means of torsion spring 59.

In order to elevate the head 27, and the load 50 carried thereby, the operating handle is oscillated or swung up and down. During the downward stroke the operating pawl 52 will engage a tooth of ratchet wheel 37 and cause the ratchet wheel and driving pinion 36 to rotate with the handle 55 through this short downward arc thus swinging the lifting bell-crank upwardly through a short arc. The holding pawl 57 will snap outwardly over the teeth of the ratchet, but will engage another tooth of the ratchet wheel to hold the load 60 elevated during the succeeding upward movement of the operating handle, during which movement the operating pawl 52 will ride outwardly over the teeth of the ratchet wheel. In this manner, continuous swinging movement of the operating handle will cause a step by step upward swinging movement of the lifting bellcrank until head 27 has been raised to the elevated position shown in dotted lines in Fig. 1.

A suitable reversing mechanism is provided so 70 that this same up and down swinging movement of the operating handle may be utilized to lower the lifting head and the load supported thereby. This reversing mechanism comprises a rotary reversing member 60 which has a hub 61 journaled 75

through bushing 62 on the shaft 32 between the ratchet wheel 37 and the handle arm 41. This reversing member is formed with a pair of outwardly projecting fingers or cam members 63 and 64 which, in certain positions of the reversing member, are adapted to engage and cooperate with the lugs 55 on the respective pawls 52 and 57. A link or rod 65 has one end portion pivotally secured in an ear 66 projecting upwardly from reversing member 60, the rod projecting rearwardly through a guide opening 67 in the handle-yoke structure and being pivotally connected with an ear 68 projecting upwardly from the casing 69 which houses the reversing spring 70. The spring 15 70 surrounds the inner end portion of a link or rod 71 which projects through the rear end of casing 69, the spring being confined between this end of the casing and a nut 72 adjustably threaded on rod 71. The rear end of rod 71 is secured 20 to a slide member 73 mounted on the side handle bar 43 (see Fig. 1). A reversing lever 74 is pivotally mounted in a bracket 75 secured to one side of handle bar 47 adjacent the hand grip 48. A link or rod 76 connects the reversing lever 25 74 with the slide member 73.

During the normal elevating operation of the jack the reversing lever 74 is swung forwardly to the position shown in Figs. 1 and 2a. When the lever is in this position the reversing spring 30 70 is not under compression, and as the operating handle is oscillated up and down the reversing cam 60 will swing idly with the handle and the reversing lugs 63 and 64 will remain out of engagement with the lugs 55 on the pawls, and these pawls operate as already described to permit a step by step upward movement of the elevating bell-crank.

When the jack is to be lowered, the reversing lever 74 is swung rearwardly, or to the dotted line position shown in Fig. 2a. This will draw the 40 slide 73 to the rear and through link 71 will place the reversing spring 70 under compression. The compression of this spring will tend to rotate the reversing member 60 in a clockwise direction so as to bring the fingers or cams 63 and 64 into 45 engagement with the lugs 55 on the pawls at certain times. As a result, the holding pawl 57 will be held out of engagement with ratchet 37 during a portion of the upward stroke of the handle so as to permit the load to be lowered, and the operating pawl 52 will be held out during the succeeding downward stroke of the handle, at which time the pawl 57 will again engage the ratchet to hold the load in its partially lowered position. The operation of this reversing mechanism is described more in detail in the Walker Patent 55 1,949,095 hereinabove referred to, in which this reversing mechanism is disclosed and claimed. The lifting jack as thus far described is substantially the same, except for certain improvements 60 in design, as the one disclosed and claimed in said Walker patent. The improvements of this present invention are concerned more especially with the novel quick-lift mechanism now about to be described.

65 Since this jack is very powerful, the elevating movement of the lifting head is necessarily proportionately slow, and it is desirable to provide means for quickly elevating the head until it is in position to engage the load. For this purpose 70 the auxiliary quick-lift mechanism is provided. The reciprocating bar 77 is guided at 78 (see Fig. 5) in the handle yoke frame 40 and the forward under portion of bar 77 is formed with a rack 79 which meshes with the auxiliary pinion 39 already 75 described. A link or push-rod 80 is pivotally con-

nected at one end 81 with the rear end of bar 77, and is pivotally connected at its other end 82 with a slide member 83 mounted on the handle bar 47 so as to be movable longitudinally thereof. The slide 83 is provided with suitable laterally extending hand grips 84 or other means by which the slide 83 may be conveniently moved longitudinally of the handle.

When the jack has been pushed into proper position beneath the automobile axle or other load to be lifted, the operator will grasp the handle 84 on slide 83 and pull this slide rearwardly along the operating handle 47, this pull being transmitted through rod 80 to the rack 79 which will rotate the pinions 39 and 36 and cause 10 the lifting bell-crank to be swung quickly upwardly so as to swing the lifting head 27 into engagement with the load. During this operation the pawls 52 and 57 will simply ride over the ratchet teeth of ratchet wheel 37. As soon as 15 the load is engaged the handle 84 will be released and the remainder of the lifting operation will be accomplished by swinging or oscillating the operating handle up and down in the manner already described. During this additional lift- 20

ing movement the rack 79 will be moved rearwardly slowly by the rotation of pinion 39 with the driving pinion 36, and the slide member 73 will be moved idly along the handle bar 47. When the jack is lowered the slide 83 will, in a reverse manner, be moved along the handle bar 47 in an opposite direction by the pull transmitted through rod 80 from rack 79. It will be apparent that this improved quick-lift mechanism is very simple and effective, and is self-reversing so that the device will always be in 30 position to impart a quick lift to the bell-crank when such movement is desired.

It will be noted that the operations of this jack are controlled entirely from the handle, and that an operator positioned adjacent the rear end of the handle can manipulate the jack into position beneath the load, quickly raise the lifting head into engagement with the load, and then raise and lower the load, without changing his position. 40

I claim:

1. In a lifting jack, a supporting member, a load-lifting member movably mounted in the supporting member and comprising a rack, a pair of connected pinions rotatably mounted in the supporting member, one of the pinions meshing with the rack, a second rack meshing with the second pinion, and means for moving the second rack longitudinally.

2. In a lifting jack, a supporting member, a load-lifting member movably mounted in the supporting member and comprising a rack, a pair of connected pinions rotatably mounted in the supporting member, one of the pinions meshing with the rack, a second rack meshing with the second pinion, a handle pivotally connected with the supporting member, and means carried by the handle for moving the second rack longitudinally.

3. In a lifting jack, a supporting member, a load-lifting member movably mounted in the supporting member and comprising a rack, a pair of connected pinions rotatably mounted in the supporting member, one of the pinions meshing with the rack, a second rack meshing with the second pinion, a handle pivotally connected with the supporting member, a slide member mounted on the handle for movement longitudinally thereof, and a pull-rod connecting the slide member and the second rack.

pinion, and a quick-lift mechanism comprising a second pinion connected with the first pinion, a second rack meshing with the second pinion, and means carried by the handle for moving the second rack longitudinally.

18. In a lifting jack, a carriage, a load-lifting lever pivotally mounted in the carriage and comprising an arcuate rack, a pinion rotatably mounted in the carriage and meshing with the rack, a handle pivotally connected with the carriage, means actuated by oscillation of the handle for imparting step-by-step rotation to the pinion, and a quick-lift mechanism comprising a second pinion connected with the first pinion, a second rack meshing with the second pinion, a slide member mounted on the handle for movement longitudinally thereof, and a pull-rod connecting the slide member and the second rack.

19. In a lifting jack, a carriage, a load-lifting lever pivotally mounted in the carriage and comprising an internal arcuate rack, a shaft mounted in the carriage, a pinion on the shaft meshing with the rack, a ratchet-wheel on the shaft rotatable with the pinion, a holding pawl mounted in the carriage and engaging with the ratchet, a handle pivotally mounted in the carriage, an actuating pawl mounted on the handle and engaging with the ratchet, a reversing mechanism adapted to engage the pawls, means for alter-

natively positioning the reversing mechanism so that oscillation of the handle will either raise or lower the lifting lever step-by-step, and a quick-lift mechanism comprising a second pinion rotatable with the first pinion, a second rack meshing with the second pinion, and means carried by the handle for moving the second rack longitudinally.

20. In a lifting jack, a carriage, a load-lifting lever pivotally mounted in the carriage and comprising an internal arcuate rack, a shaft mounted in the carriage, a pinion on the shaft meshing with the rack, a ratchet-wheel on the shaft rotatable with the pinion, a holding pawl mounted in the carriage and engaging with the ratchet, a handle pivotally mounted in the carriage, an actuating pawl mounted on the handle and engaging with the ratchet, a reversing mechanism adapted to engage the pawls, means for alternatively positioning the reversing mechanism so that oscillation of the handle will either raise or lower the lifting lever step-by-step, and a quick-lift mechanism comprising a second pinion rotatable with the first pinion, a second rack meshing with the second pinion, a slide member mounted on the handle for movement longitudinally thereof, and a pull-rod connecting the slide member and the second rack.

JOSEPH J. MIZER.
